Attorneys.

UNITED STATES PATENT OFFICE.

EDWIN BARNES, OF SHEFFIELD, ENGLAND.

SPRING.

1,419,005.

Specification of Letters Patent. Patented June 6, 1922.

Application filed February 19, 1921. Serial No. 446,397.

To all whom it may concern:

Be it known that I, EDWIN BARNES, a subject of the King of England, residing at Sheffield, in England, have invented certain new and useful Improvements in or Relating to Springs, of which the following is a specification.

This invention relates to springs which are normally bent when unflexed, especially those bent in a curve, its object being to provide an improved method and means for protecting the spring from damage or fracture by the application of a straightening force exerted to excess.

According to the present invention the spring is protected by the employment of a relatively rotatable sheath arranged between stops adjacent to each end of the bend and comprising a number of perforated bead like bodies which are small in relation to the bent or curved part of the spring. Such bead like bodies may extend along the whole length of spring to be protected, or they may be divided into groups or units separated by springs which are preferably helical coils, the groups of beads and springs being preferably all of the same length respectively.

The method and means of protecting a bent or curved spring according to the present invention may be applied in many circumstances, but the present invention is particularly applicable to the protection of a spectacle hook side or like ear spring, such as the spring employed to anchor one end of the safety chain of a pair of eye-glasses to the ear of the wearer.

The accompanying drawing is an elevation of a spectacle hook side to which the present invention is applied.

In carrying out the present invention the bent or curved part of the spring 1 is enclosed in a relatively rotatable sheath which is flexible as a whole in the directions at right angles to its length but is substantially rigid in transverse section. In the construction illustrated the sheath is formed by groups of bead-like bodies 6 which are threaded on to the spring between a collar 4 adjacent to or beyond one end of the bend and a bead 5 at the other end. Each group of bead-like bodies is separated from the next by a helical spring 2, the collar 4 and head 5 on the spring 1 thus act as thrust-surfices or abutments against which the ends of the series of beads 6 may rotate and

are pressed by the springs 2. The collar 4 and head 5 also limit the longitudinal movement of the beads 6 and springs 2 on the spring 1.

Each group of bead like bodies 6 and each spring 2 is preferably of substantially the same length as illustrated.

The sheath extends along the whole of the bent or curved part of the spring 1 and may if desired extend also along the whole of the straight part of the spring. The extent of the spring covered by the sheath is governed by the distance apart at which the straightening force on the spring is likely to be applied, the intention being that both or all points at which the straightening force is applied shall be on the sheath. The sheath being flexible as a whole in directions at right angles to its length will not prevent the spring from performing its normal functions, but when the result of applying a straightening force approaches the limits of safety the sheath being substantially rigid in transverse section, will allow the spring to twist or turn inside it thus converting the straightening force into a torque, and preventing the spring from being damaged or fractured.

The bodies 6 themselves are small in relation to the curve of the spring 1 and their contacting sides are preferably rounded or bevelled in order to attain the desired flexibility in directions at right angles to the length of the sheath as a whole. If desired the bead like bodies 6 may be in contact with one another throughout the whole length of the extent of the sheath instead of being separated into groups or units provided some form of spring is furnished to hold the bodies 6 in contact with one another.

Although the invention is illustrated as applied to a spring which is circular in cross-section, it may of course be employed for protecting bent or curved springs of other shapes in cross-section provided the spring is rotatable in the sheath when under the action of the straightening force.

What I claim and desire to secure by Letters Patent is:—

1. Means for protecting a bent spring from damage due to a straightening force comprising the combination with the bent spring, of a plurality of perforated bead-like bodies small in relation to the bend of the spring threaded on the bend thereof, stops on the spring disposed with the bend

between them and a spring encircling the bend between the stops and maintaining a series of contacts between stops, beads and spring.

- 5 2. Means for protecting a bent spring from damage due to a straightening force comprising the combination with the bent spring, of a plurality of perforated bead-like bodies small in relation to the bend of 10 the spring threaded on the bend thereof, stops on the spring disposed with the bend between them and a helical spring encircling the bend between the stops dividing the bead-like bodies into groups and maintaining 15 a series of contacts between stops, beads and spring.
3. Means for protecting a bent spring from damage due to a straightening force comprising the combination with the bent 20 spring, of a plurality of perforated bead-like bodies small in relation to the bend of the spring threaded on the bend thereof, stops on the spring disposed with the bend between them and a number of helical 25 between the stops dividing the bead-like bodies into

groups and maintaining a series of contacts between stops, beads and springs, each group of beads and each spring being of substantially the same length. 30

4. The combination with a spectacle hook side or like springs of means for protecting the hook portion thereof from damage due to a straightening force comprising the combination with the hook portion, of a plurality of perforated bead-like bodies small in relation to the bend of the hook threaded on the bend thereof, stops on the side disposed with the bend between them and a number of helical springs encircling the bend between the stops dividing the bead-like bodies into groups and maintaining a series of contacts between stops, beads and springs, each group of beads and each spring being of substantially the same length. 35 40

45 In testimony whereof he affixes his signature.

EDWIN BARNES.
